UNITED STATES PATENT OFFICE.

WILLIAM F. IRRGANG, OF CHICOPEE, MASSACHUSETTS, ASSIGNOR TO THE FISK RUBBER COMPANY, OF CHICOPEE FALLS, MASSACHUSETTS, A CORPORATION OF MASSACHUSETTS.

BEVELING AND SEALING CLAMP.

Application filed August 12, 1925. Serial No. 49,639.

My present invention relates to devices for sealing the ends of rubber tubes to mandrels during vulcanization and for simultaneously skiving the ends of the tubes so as to prepare them for splicing into endless form at a later stage. One object of the present invention is to provide a clamp which will in operation be entirely self-contained, all parts being united into one piece which may be handled as a unit. Another object is to provide a clamp which may be slipped over the end of the tube and tightened in place by a simple motion readily performed by machinery. Another object is to provide a clamp in which the means which hold it closed on the tube are of the utmost simplicity, both as to their construction and their operation. Other and further objects will appear from the following description and claims.

Referring to the drawings,

Fig. 1 is an end view of a clamp constructed in accordance with my invention;

Fig. 2 is a sectional view of the same, taken on line 2—2 of Fig. 3;

Fig. 3 is a sectional view taken on line 3—3 of Fig. 2; and

Fig. 4 is a section on line 4—4 of Fig. 2.

The clamp is enclosed in a casing 10 which contains all of the parts except two operating lugs which will be described later. At one point the casing is formed with an inwardly extending boss 11 which serves as a support for a flexible band 13 which does the actual skiving of the tube. This band is made of spring metal formed in the shape of the frustum of a cone and having its ends tapered as at 14 so as to overlap each other and at the same time present a smooth surface to the rubber. The band may be attached to the boss 11 as by a rivet 15. Fitting closely within the casing 10, and sliding frictionally on the band 13 are two blocks 16, each provided with lugs 17 extending through slots 18 in the casing and projecting beyond the casing as mentioned before. The blocks have a running fit in the casing and have their inner surfaces grooved to receive the band 13 as is best shown in Fig. 4. The ends of the band 13 are preferably so arranged as to overlap when the clamp is in the expanded position of Fig. 1. By this construction the ends of the band are always guided on

each other during the closing movement and 55 there is no danger of these ends becoming misplaced with consequent mutilation of the tube.

In Fig. 1 the lugs 17 have been shown as in the positions that they assume when the clamp is expanded so as to permit its application to or its removal from the tube. In Fig. 2 the lugs have been shown in the positions they assume when the clamp is in place on the tube. The mounting of the band 13 is somewhat eccentric, being, in the position of the clamp as shown in the drawings, nearer the top of the casing than its bottom. As the blocks are moved from the position of Fig. 1 to that of Fig. 2, they bear on the band and cause the latter to contract upon the underlying rubber. The ends of the band are so tapered that its inner surface is maintained substantially circular during the closure of the clamp. 70 As the clamp is closed by the action of the blocks in moving from the position of Fig. 1 to that of Fig. 2, the increasing friction on the band will hold them tightly in place without the necessity for other means for this purpose. The clamp will retain itself in closed position until it is desired to open it after vulcanization of the tube, when it is a simple matter to move the lugs back to the position of Fig. 1. The band will thereupon spring back to the larger diameter and will permit the clamp to be readily withdrawn from the tube.

The smaller edge of the band 13 is preferably formed with the inner corner 19 sharp in order to cut the rubber at this point and permit the removal of any excess rubber before vulcanization. For a similar reason the edge of the blocks are cut away at 20. The action of the clamp in skiving the end of the tube is shown in Fig. 3, and it is thought that the operation of the device will be clear from what has been said. Changes in the construction of the parts may of course be made within the scope of the invention as pointed out in the following claims.

Having thus described my invention, I claim:

1. A beveling and sealing clamp for use 105 on rubber tubes which comprises an outer casing, an inner flexible band secured in the casing and formed as the frustum of a

cone, and means retained by the casing and engaging the band frictionally so that when the band is contracted upon a rubber tube such friction will of itself hold the clamp closed.

2. A beveling and sealing clamp comprising a hollow casing, a flexible band of spring metal held in the casing with its ends overlapped, and blocks sliding in the casing and bearing frictionally on the band, said blocks being movable eccentrically in

relation to the band to cause the band to be contracted.

3. A beveling and sealing clamp for use with rubber tubes which comprises a casing, a split band eccentrically mounted in the casing, and a plurality of blocks concentrically mounted in the casing and bearing frictionally on the band, said blocks having lugs projecting outside the casing to afford means whereby the clamp may be operated.

WILLIAM F. IRRGANG
